(57) **CLAIM**

The ornamental design for a car seat clip, as shown and described.

DESCRIPTION

FIG. 1 is an isometric view of the car seat clip embodying the present ornamental design;

FIG. 2 is left side view thereof;

FIG. 3 is a right side view thereof;

FIG. 4 is a front view thereof;

FIG. 5 is a top plan view thereof;

FIG. 6 is a rear view thereof; and,

FIG. 7 is a bottom plan view thereof.

The shading in the drawings represents texture and forms no part of the claimed design.
